LOCKING OF STEREOPLATES OR PRINTING SURFACES TO THE CYLINDERS OF ROTARY PRINTING MACHINES

Robert Bradshaw, Preston, England

Application March 27, 1934, Serial No. 717,670
In Great Britain October 16, 1933

9 Claims. (Cl. 101—378)

This invention relates to improved means for locking stereoplates or printing surfaces to the cylinders of rotary printing machines.

Locking arrangements for the above purpose are already known wherein on a four plate wide printing cylinder, the inner plates can be unlocked without unlocking the outer plates, all the dogs necessary to lock or unlock the plates being operated by means of screwed rods from the ends 10 of the cylinder.

The present invention has for its object to provide improved means whereby any individual plate on a printing cylinder can be adjusted longitudinally and peripherally on the cylinder.

According to the invention the usual fixed centre margin ring is adjustable and is formed in two parts each part carrying clamping jaws to engage the stereoplates.

The clamping jaws on these two rings are interspaced and one ring is controlled from one end of the cylinder by means of screwed rods connected by gears while the other ring is controlled from the opposite end of the cylinder by similar mechanism. The arrangement is such that the jaws on one ring move between the jaws on the other ring so that the space required is very little more than is necessary for the usual fixed margin ring. This adjustable centre margin ring provides a means of adjustment for longitudinal register of the inner plates. The outer plates are registered longitudinally by means of the outside dogs carried on screwed sleeves geared together and operated in the known manner. Each set of inner and outer plates is locked by means of an expanding ring made in two parts coupled together by ring-expanding screws operated by spindles passing out to the end of the cylinder as hereinafter described. Each part of the ring carries clamping jaws, the jaws being interspaced and arranged as in the case of the centre ring previously described.

The adjustment of the stereoplates in a peripheral direction is effected by means of bolts having tommy heads mounted in bars fixed to the surface of the printing cylinder.

To enable the invention to be fully understood it will now be described by reference to the accompanying drawings in which:—

Fig. 1 is an end elevation of a printing cylinder having one form of the invention applied thereto, and

Fig. 2 is a development of the printing cylinder with the ends in section.

Figs. 3, 4, 5 and 6 are longitudinal sections

of portions of the cylinder showing the lock-up mechanism and details of its operation.

In the drawings the invention is shown as applied to a printing cylinder which is four plates wide and two plates round. Each set of lock-up mechanism comprises two plates so that there are four sets of lock-up mechanism per cylinder.

Since the lock-up mechanism is similar for each pair of plates only the mechanism for one pair of plates shown on the right hand side of Fig. 2 will be described.

The printing cylinder 7 is grooved peripherally at 8, 9, 10 to receive the locking ring 11, the centre margin ring 12 and the locking ring 13 respectively. Each ring is formed in two parts, 15 each part carrying clamping teeth 14 for engaging the adjacent stereoplates.

It will be noted that the teeth 14 on each pair of rings are interspaced, and the teeth on one ring move between the teeth on the other ring. 20

The centre margin ring 12 comprises the two parts *a*, *b*, the ring *a* being controlled from the left hand end of the cylinder and the ring *b* from the opposite end. Each ring *a*, *b*, is controlled from the appropriate end of the cylinder by several spindles 15, the spindles being geared together on the cylinder end by wheels 16 and intermediate wheels, one of the spindles having a squared end 17 for an operating spanner (Fig. 4).

Each locking ring comprises the two parts *c*, *d*, and these two parts are adapted to be moved apart to lock the plates by the mechanism shown in Fig. 5.

This mechanism comprises screws 18 each having a squared pocket 19 with which the squared end of a spindle 20 engages. The spindles 20 pass through sleeves 21 which are externally threaded and carry dogs 22 for the outer plates. The spindles are geared together by wheels 23 and the sleeves by wheels 24 and intermediate wheels mounted on the cylinder end. One spindle has a squared end 25 and one of the intermediate wheels 26 (Fig. 3) a squared end 27, for operation by a key or spanner.

By operating the sleeves 21, the dogs 22 are adjusted to register the outer plate and by operating the spindles 20 the rings *c*, *d* are forced apart to lock up the adjacent plates. The rings are held against the cylinder by keepers 28, so that they can be adjusted longitudinally but cannot lift from the body of the cylinder.

The lock-up arrangement shown in Fig. 5 is suitable for use with stereoplates of fixed width. In Fig. 6 a modified arrangement is shown which

enables a column change to be made in the width of the plates.

In this arrangement the ring-expanding screw 29 has a squared portion 30 which is engaged by a squared pocket in a sleeve 31 mounted on the spindle 32. The sleeve 31 is operated by means of a cotter 33 on spindle 32 engaging a slot 34 in the sleeve. A removable ring 35 of column width is fitted to the cylinder adjacent to the ring *c* a recess 36 being formed beneath same to receive the screw 29. This ring 35 can be lifted out and the rings *c*, *d* can be shifted by hand across the cylinder to replace the ring 35, the latter then being inserted into the cylinder on the right hand side of the ring *d*. The slotted connection of the spindle and sleeve enables the rings *c*, *d* to be controlled as before but in the new position.

The plates are adjusted in the peripheral direction by means of screws 37 carried in bars 38 secured to the cylinder and having tommy heads which engage the edges of the plates. Such adjustments are provided for both the inner and outer plates.

It will be understood that the invention can also be applied to a two plate wide cylinder.

I claim:—

1. Means for locking stereoplates to printing cylinders comprising in combination locking elements at the side margins of the cylinder, means for controlling said locking elements, a central margin ring formed in two parts, dogs carried by each ring part for clamping the adjacent edges of two plates, means to adjust the relative positions of said ring parts, the control of one ring part being effected from one end of the printing cylinder and the control of the other ring part from the opposite end of the cylinder.

2. Means for locking stereoplates to a printing cylinder according to claim 1 in which the dogs on the two parts of the centre margin ring are interspaced and move one between the other.

3. Means for locking stereoplates to a printing cylinder comprising locking elements at the side margins of the cylinder, means for controlling said elements, a central margin ring formed in two parts, dogs carried by each part for clamping the adjacent edges of two plates, each ring part being controlled from opposite ends of the cylinder by means of screwed spindles geared together, the end of one of the spindles being shaped to receive a key whereby it may be turned.

4. Means for locking stereoplates to a printing cylinder comprising a central margin locking ring formed in two parts, dogs carried by each part for clamping the adjacent edges of two plates, spindles operated from opposite ends of the cylinder for controlling each of said ring parts and geared together at their respective ends of the cylinder for operation by a spanner or key, sleeves mounted on said spindles and carrying dogs for locking the outside edges of

the plates, said sleeves being also geared together, and intermediate gears between the spindle and sleeve gearing where necessary.

5. Means for locking stereoplates to a printing cylinder comprising in combination locking elements at the side margins of the cylinder, means for controlling said locking elements, a central margin ring formed in two parts, dogs carried by each ring part for clamping the adjacent edges of the two plates, sleeves connected to each part by threaded members, slots in said sleeves, and cotters connecting the sleeves to spindles operated from the cylinder ends, the cylinder being also fitted with a ring of column width which can be moved to either side of the central two part margin ring by altering the position of the cotters in the slots of the sleeves.

6. Means for locking stereoplates to a printing cylinder comprising in combination locking elements at the side margins of the cylinder, means for controlling said locking elements, a central margin ring formed in two parts, dogs carried by each ring part for clamping the adjacent edges of two plates, means to adjust the relative positions of said ring parts, each part being controlled from opposite ends, bars being also fitted to the cylinder to carry bolts or screws having tommy heads by which the stereoplates may be adjusted in a peripheral direction.

7. Means for locking the stereoplates to a two plate wide printing cylinder comprising in combination a central two part margin ring arranged between the plates, means at the opposite ends of the cylinder for controlling said ring parts, and dogs for holding the outer edges of the plates carried by threaded spindles connected at the ends of the cylinder with trains of gears, one of the spindles of each plate being shaped for operation by a key.

8. Means for locking stereoplates on a four plate wide printing cylinder comprising in combination a central margin ring formed in two parts and arranged between the two inner plates, dogs on each part of the margin ring, two-part rings arranged between the outer and inner plates, dogs on each ring part, locking elements at each side margin of the cylinder adapted to engage the outer plates, spindles controlled from opposite ends of the cylinder for operating each ring part of the two-part rings and of the central margin ring, sleeves mounted on said spindles also controlled from the cylinder ends for operating the locking elements at the side margins of the cylinder, and gearing at the cylinder ends interconnecting the spindles and the sleeves.

9. Means for locking stereoplates on a four plate wide cylinder according to claim 8 wherein the dogs on the central margin ring and the two-part rings arranged between the inner and outer plates are interspaced and move one between the other.

ROBERT BRADSHAW.
